[57] CLAIM

The ornamental design for an eyeglass wrap, as shown and described.

DESCRIPTION

FIG. 1 is a front elevational view of an eyeglass wrap showing my new design, the broken lines shown in FIGS. 1 and 2 being understood to represent stitching;

FIG. 2 is a back elevational view of the eyeglass wrap of FIG. 1;

FIG. 3 is a left side elevational view of the eyeglass wrap of FIG. 1;

FIG. 4 is a right side elevational view of the eyeglass wrap of FIG. 1;

FIG. 5 is a top plan view of the eyeglass wrap of FIG. 1; and,

FIG. 6 is a bottom plan view of the eyeglass wrap of FIG. 1.
